PACKAGE OF TRAYS

Nathan L. Solomon, Englewood, N. J.

Application October 6, 1949, Serial No. 119,826

13 Claims. (Cl. 206—65)

1

This invention relates to an article of manufacture comprising a tray-like member disposed upon a mounting, wherein a plurality of articles are supported in the member and held against displacement from the tray by means engaging said mounting. More particularly, the invention deals with an article of the character described, wherein the tray-like member is divided centrally into separate compartments and the intermediate wall is shaped to form means in connection with which the articles operate to perform a function or operation on the article such, for example, as the spreading of bobby-pins.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a plan view showing a pair of the trays coupled together.

Fig. 2 is a section on the line 2—2 of Fig. 1.

Fig. 3 is a section on the line 3—3 of Fig. 1, showing two pairs of trays.

Fig. 4 is a perspective view of the container with part of the construction broken away; and

Fig. 5 is a view similar to Fig. 2 showing a modification.

In the drawing, I have shown an article of manufacture in the form of a tray-like member 10 disposed upon a suitable mounting 11 and a number of these articles are adapted to be assembled in nested relationship to each other to form pairs and one pair nests with adjacent pairs in forming an assemblage of a dozen or more articles in a container, such as indicated at 12 in Fig. 4 of the drawing. By virtue of the construction and assemblage of the articles in pairs, they may be conveniently packed in a rectangular container, such as 12, and the only necessity is to fill opposed corner portions 13, 13' of the container with corrugated or other filling, as will be apparent.

Returning now to the structure of each article, this is shown in detail in Figs. 1, 2 and 3 and a modified form of construction in Fig. 5. As each article of manufacture is of the same structure, the brief description of one will apply to all articles. The tray member 10 has upstanding peripheral side and end walls 14 and 15, respectively, the side walls being joined by a central partitioning portion 16, comprising spaced wall portions 17, 17' which form, intermediate the side walls 14, a large opening 18. The walls 17, 17'

2

have inwardly set upper portions 19, 19' integrally joined in an upwardly extending relatively wide bevelled or contraction portion 20, terminating in a sharp upper edge 21. The walls 17, 17', 19, 19' have large rectangular openings therein, as indicated at 22 and these openings form shallow central portions of the walls 17, 17', as indicated by the surfaces 23. The end walls 15 are also provided with recesses 24 forming surfaces 25, somewhat similar to the surfaces 23. It will be apparent that the portion 20 is of less depth than the depth of the tray, thus leaving shoulder portions 26 on the tray at ends of the portion 20.

15 The mounting card 11 is secured to the bottom of the tray. The card proper is of a width corresponding to the width of the tray or, in other words, side edge portions 27 of the card are in alinement with outer surfaces of the walls 15, and one end 28 of the card is in alinement with one of the walls 14. The card has an extension beyond the other wall 14 which is of a width similar to the distance between the outer surfaces of the walls 14 so as to receive a companion 20 article of manufacture or the tray portion or member thereof.

The card 11 has two elongated apertures 29, 29', one disposed beneath and registering with the opening 18 and the other adapted to register with the tapered spreader portion 20 of a companion tray in the manner clearly illustrated in Fig. 1 of the drawing. In other words, the length of the apertures 29, 29' is slightly greater than the greatest width of the member, so as to freely receive the member 20 of a companion article of manufacture in the nesting of such articles for packaging, as illustrated in Fig. 4. It will clearly appear that the member 20 has a bevelled wall socket portion 30 tapered to receive the member 20 of the companion article.

30 In the construction shown in Figs. 1, 2 and 3 of the drawing, the mounting card 11 has, integrally with the side edges 27, tab or flap portions 31 which flare outwardly to a slight extent 35 and these tab or flap portions are adapted to fold around each of the compartments 32, 32' of the tray passing through the recesses 24 and apertures 22 and seating on the surfaces 25 and 23, respectively. The end portions of the tabs or 40 flap portions 31 extend downwardly through the opening 18 and onto the lower surfaces of the mounting cards 11, as seen at 33, and are secured in this position by a gummed or Scotch tape 34 or in any desired manner.

45 The flaps or tabs are arranged in the positions

stated above after a predetermined number of bobby-pins or other articles 35 have been arranged in each of the trays 32, 32' and these flaps or tabs securely retain the articles against displacement from the trays and, at the same time, retain the cards 11 on the tray members 16 to constitute a part thereof. The articles are packed and shipped in this manner and are also sold on the retail counter in the manner defined. In this connection, it will be apparent that the extended portion of the mounting card having the aperture 29' therein can be utilized as a means for hanging the tray for display purposes.

Considering Fig. 5 of the drawing, here a tray 10' is shown which is identical with the tray shown in Figs. 1 to 3, inclusive, and for this reason no further detailed description of this tray will be given. However, substituted for the card 11 is a card 36 which differs from the card 11 solely in the fact that the flaps or tabs 31 are dispensed with. In other words, in Fig. 5, each half of the card will be equivalent to the base dimensions of the tray member 16 and will have apertures therein, as at 37, similar to the apertures 29, 29'. To hold the card 36 in place as well as to secure the articles in the tray portions of the tray member, a single strip or band of Scotch tape 38 or the like is employed and this tape envelopes both of the tray portions and the articles therein and the ends 39, 39' of the Scotch tape are brought beneath and secured to the lower surface of the card 36, as clearly seen. With this type of construction, it is also possible to use a display or advertising card 40 of any desired shape or form, frictionally held within the apertured portion of the partitioned member of the tray and extending over the tray compartments in the manner indicated.

With my improved construction, it will be apparent that the articles of manufacture, when completely formed, are conveniently stacked side by side and one upon another. This is done by disposing two articles which are arranged side by side, in other words, with the walls 16 abutting and the articles in inverted position with respect to each other, that is to say, one article will have its spreader extension 20 directed upwardly to pass through the aperture 29' of the other article; whereas said other article has its spreader member 20 directed downwardly and extending through the aperture 29' of the first named article.

Now in stacking the articles one upon the other for packaging, it will appear that the spreader extension 20 of one pair of articles will extend into the aperture 18 of the adjacent pair so that, in the final packaging, the tray portions of all of the articles at one side of the box will have their members 20 directed upwardly and, at the other side downwardly. The terms "downwardly" and "upwardly" are used solely in a descriptive sense and not in the position assumed in the resulting wrapper box 12, as seen in Fig. 4 of the drawing.

Briefly stated, each pair of articles disposed side by back are interlocked and each pair of such articles are interlocked with adjacent pairs disposed on opposed sides of the first named pair, thus when a complete series of pairs of articles are assembled, the entire group can be conveniently handled for placement in the final packaging box 12.

It will be apparent that other types of arrangements of packings may be provided but, in all instances, an interlocking or intercoupling en-

gagement between adjacent pairs will be provided. Furthermore, articles of manufacture of the kind under consideration can be made for the merchandising of various types and kinds of products, particularly where display in the merchandise in the resulting tray compartments is provided. In this latter instance, it is not essential that the articles be necessarily loose or freely disposed in the compartments.

After the article has been purchased by a consumer, the card is removed from the tray member by withdrawing the flaps or tabs 31 or removing the Scotch tape 38. This operation displaces the card from the tray member and frees the articles for removal from the tray compartments. When such articles are in the form of bobby-pins, the pin can be moved over the spreader 20 to spread the pin sufficiently to be grasped by the hand for insertion into the hair. In this respect, the tray provides means for accomplishing an operation of spreading bobby-pins by a single hand, thus materially facilitating the use of such pins in placement in the hair.

From the foregoing, it may be particularly noted that the present invention provides an article and package created to provide, a dual compartment for the storage of bobby-pins, so that the user may advantageously pick-up pins with either hand from either side of the box without interference from the projecting wedge; a pin opening projection projecting above the stored pins sufficiently high to not interfere with same; an opener centrally disposed, so that there is little or no likelihood of the user toppling over the box when opening pins; cooperating wedges and sockets to prevent relative shifting between boxes, etc. The articles are preferably each provided with recesses 24 on the end walls and similar recesses in the inner walls 17, 17'. The cards 11 have tabs 31 extending upwardly along the end walls through the recesses 24 over bobby pins supported in the article through the recesses in the inner walls, then downwardly on said inner walls and onto the lower surface of the cards. The tabs are secured to the lower surfaces of the cards by the strips 34 of "Scotch tape" or the like. It will be noted that the recesses 24 are sufficiently deep so that the tabs provide downward pressure upon the bobby pins supported in the tray. With this construction, a strong and secure holding of the bobby pins in the tray is provided.

Having fully described my invention, what I claim as new and desire to secure by Letters Patent is:

1. An article of manufacture of the character described comprising a card having apertured end portions, a tray-like member disposed upon one apertured end portion, said member having a central partition portion dividing the tray into independent compartments, the partition portion having an aperture opening through the lower surface of the tray and registering with the aperture in the end portion of said card, and means extending over each compartment of the tray and secured to said card for supporting articles in the tray compartments against displacement.

2. An article of manufacture of the character described comprising a card having apertured end portions, a tray-like member disposed upon one apertured end portion, said member having a central partition portion dividing the tray into independent compartments, the partition portion having an aperture opening through the

lower surface of the tray and registering with the aperture in the end portion of said card, means extending over each compartment of the tray and secured to said card for supporting articles in the tray compartments against displacement, and the walls of the tray and said partition being apertured to receive said last named means.

3. An article of manufacture of the character described comprising a card having apertured end portions, a tray-like member disposed upon one apertured end portion, said member having a central partition portion dividing the tray into independent compartments, the partition portion having an aperture opening through the lower surface of the tray and registering with the aperture in the end portion of said card, means extending over each compartment of the tray and secured to said card for supporting articles in the tray compartments against displacement, and said partition having an upwardly projecting contracted member extending above upper edges of the walls of the tray.

4. An article of manufacture of the character described comprising a card having apertured end portions, a tray-like member disposed upon one apertured end portion, said member having a central partition portion dividing the tray into independent compartments, the partition portion having an aperture opening through the lower surface of the tray and registering with the aperture in the end portion of said card, means extending over each compartment of the tray and secured to said card for supporting articles in the tray compartments against displacement, said partition having an upwardly projecting contracted member extending above upper edges of the walls of the tray, and a companion similar article being adapted to be coupled with the first named article by insertion of said projecting contracted portion of the second article through the other apertured end portion of the card of the first article and with the tray of the second article in inverted position with respect to the tray of the first article.

5. An article of manufacture of the character described comprising a card having apertured end portions, a tray-like member disposed upon one apertured end portion, said member having a central partition portion dividing the tray into independent compartments, the partition portion having an aperture opening through the lower surface of the tray and registering with the aperture in the end portion of said card, means extending over each compartment of the tray and secured to said card for supporting articles in the tray compartments against displacement, and said means comprising a pair of flaps extending integrally from side edge portions of the card and downwardly through the aperture of said partition.

6. An article of manufacture of the character described comprising a card having apertured end portions, a tray-like member disposed upon one apertured end portion, said member having a central partition portion dividing the tray into independent compartments, the partition portion having an aperture opening through the lower surface of the tray and registering with the aperture in the end portion of said card, means extending over each compartment of the tray and secured to said card for supporting articles in the tray compartments against displacement, said means comprising a pair of flaps extending integrally from side edge portions of

the card and downwardly through the aperture of said partition, and means securing the ends of the flaps to the lower surface of the card.

7. A device of the class described comprising a tray defined by side and end walls, a hollow partition joining side walls and dividing the tray into separate compartments, said partition having an upstanding hollow fingerpiece portion, opposed walls of the fingerpiece portion and partition having large apertures, the hollow partition opening through the lower surface of the tray, and end walls of the tray having recesses in alignment with the apertures in said partition and fingerpiece portion.

8. A device of the class described comprising a tray defined by side and end walls, a hollow partition joining side walls and dividing the tray into separate compartments, said partition having an upstanding hollow fingerpiece portion, opposed walls of the fingerpiece portion and partition having large apertures, the hollow partition opening through the lower surface of the tray, end walls of the tray having recesses in alignment with the apertures in said partition and fingerpiece portion, and said fingerpiece portion having an upwardly contracted end terminating in a blade edge.

9. A device of the class described comprising a tray defined by side and end walls, a hollow partition joining side walls and dividing the tray into separate compartments, said partition having an upstanding hollow fingerpiece portion, opposed walls of the fingerpiece portion and partition having large apertures, the hollow partition opening through the lower surface of the tray, end walls of the tray having recesses in alignment with the apertures in said partition and fingerpiece portion, said fingerpiece portion having an upwardly contracted end terminating in a blade edge, and means secured to the tray and extending over both compartments of the tray for securing articles against displacement from said compartments.

10. A device of the class described comprising a tray defined by side and end walls, a hollow partition joining side walls and dividing the tray into separate compartments, said partition having an upstanding hollow fingerpiece portion, opposed walls of the fingerpiece portion and partition having large apertures, the hollow partition opening through the lower surface of the tray, end walls of the tray having recesses in alignment with the apertures in said partition and fingerpiece portion, said fingerpiece portion having an upwardly contracted end terminating in a blade edge, means secured to the tray and extending over both compartments of the tray for securing articles against displacement from said compartments, and said last named means comprising a strip of Scotch tape.

11. A device of the class described comprising a tray defined by side and end walls, a hollow partition joining side walls and dividing the tray into separate compartments, said partition having an upstanding hollow fingerpiece portion, opposed walls of the fingerpiece portion and partition having large apertures, the hollow partition opening through the lower surface of the tray, end walls of the tray having recesses in alignment with the apertures in said partition and fingerpiece portion, said fingerpiece portion having an upwardly contracted end terminating in a blade edge, means secured to the tray and extending over both compartments of the tray for securing articles against displacement from said

compartments, said last named means comprising a card arranged on the lower surface of the tray, members integral with side edges of the card adapted to extend over each compartment of the tray and then onto the lower surface of the card, and means securing said members to the lower surface of the card.

12. A tray for merchandising and dispensing bobby-pins, said tray being defined by side and end walls, a central partition intermediate side walls, said partition dividing the tray into independent compartments, the partition being hollow and opening through the bottom of the tray, a spreader member extending upwardly from the partition, said spreader having a contracted upper edge, end walls of the tray having recesses, said partition and spreader having apertures in alignment with said recesses, removable means extending through the apertures and recesses and onto the lower surface of the tray for normally retaining bobby-pins against displacement from each of said compartments, and said bobby-pins, upon the removal of said last named means, being adapted to move over the spreader to open the same facilitating use of said bobby- 25 pins.

13. In a device of the class described, the combination of a tray, a pair of outer side walls on

the tray, each side having an aperture, a pair of inner walls dividing the tray into a pair of compartments for parts, each inner wall having an aperture, a bottom to said tray having a recess between said pair of center walls, a card having a recess therein, a pair of integral tabs on said card adapted to locate the tray laterally with respect to the card and the recess therein and to be passed through said apertures in the side walls and the inner walls of the tray thence downwardly through the recess in the bottom and through the recess in the card for confining parts in the compartments, and said tabs being folded over and fastened to the back of the card to lock the tray and the card together.
